Primary Examiner — Leanne Was-Englehart(74) *Attorney, Agent, or Firm* — Steven A. Nielsen;
www.NielsenPatents.com(57) **CLAIM**

The ornamental design for a corner piece for reducing cracks in stucco.

DESCRIPTION

FIG. 1 is a top perspective view of the claimed corner piece for reducing cracks in stucco;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

1 Claim, 5 Drawing Sheets(56)
